(57) **CLAIM**

The ornamental design for a flower over the cabinet/drawer hanger support for household items, as shown and described.

DESCRIPTION

FIG. 1 is a perspective view of a flower over the cabinet/drawer hanger support for household items showing our new design;

FIG. 2 is a top plan view thereof;

FIG. 3 is a front elevational view thereof;

FIG. 4 is a bottom plan view thereof;

FIG. 5 is a right side elevational view thereof, the left side elevational view being a mirror image; and,

FIG. 6 is a rear elevational view thereof.

The broken showing in FIGS. 1-6 represents unclaimed subject matter and forms no part of the claimed design.

1 Claim, 3 Drawing Sheets
